UNITED STATES PATENT OFFICE.

GEORGE S. MARSHALL, OF ST. LOUIS, MISSOURI, ASSIGNOR TO THE
MISSOURI RAILWAY EQUIPMENT COMPANY, OF SAME PLACE.

DESIGN FOR A CAR-DOOR HANGER.

SPECIFICATION forming part of Design No. 31,327, dated August 1, 1899.

Application filed July 3, 1899. Serial No. 722,772. Term of patent 14 years.

To all whom it may concern:

Be it known that I, GEORGE S. MARSHALL, a citizen of the United States, residing at the city of St. Louis, State of Missouri, have invented a certain new and original Design for Car-Door Hangers, of which the following is a full, clear, and exact description, such as will enable others skilled the art to which it appertains to make and use the same, reference being had to the accompanying drawings, forming part of this specification, in which—

Figure 1 is an elevational view of the obverse side of my new and original design for door-hangers. Fig. 2 is an elevational view 15 of the reverse side of the same. Fig. 3 is a plan view of the same. Fig. 4 is a vertical longitudinal sectional view of the same, taken on the line 4 4 of Fig. 1; and Fig. 5 is a horizontal transverse sectional view of the same, 20 taken on the line 5 5 of Fig. 1.

This invention relates to a new and original design for door-hangers, the essential features of which are an inverted-U-shaped casting whose parallel members are of unequal 25 lengths, said members being provided with T-shaped orifices and ornamented by ribs, as will hereinafter be described.

a represents the inverted-U-shaped casting embodying my new and original design, the 30 same being formed by two parallel members of unequal lengths and connected at their upper ends by a loop portion *b*. The longer of said parallel members, or the one I shall designate by *c*, is provided with a T-shaped orifice *d*, a plurality of circular perforations *e*, 35 and is ornamented by a raised perimetral rib *f*. This member *c* is further ornamented

by ribs *g* and *h*, which are at the upper portion of said member arranged one on each side of the T-shaped orifice *d*, and are then so curved 40 as to cause them to converge and touch each other at the point marked *i*, after which they then diverge and by an ornamental curve blend into the border rib *f*. The shorter member of this inverted-U-shaped casting, or the 45 one designated by *j*, is provided with a T-shaped orifice somewhat similar in construction to the T-shaped orifice *d* of the member *c*, its only difference being, however, in that its vertical member is open-ended—that is, 50 said vertical member extends clear to the lower edge of said shorter member *j*.

The loop portion *b* and the shorter member *j* of the casting *a* are ornamented by causing the ribs *g* and *h* to continue thereover, which 55 ribs finally terminate at the lower end of the shorter member *j*.

The inner face of the longer member *c* of the casting *a* is formed of two different planes, said planes being divided by the edge *k*, the 60 portion below said edge *k* being arranged closer to the shorter member *j* than is that portion above said edge *k*.

Having thus described my invention, what I claim is—

The design for a door-hanger substantially as herein shown and described.

In testimony whereof I hereunto affix my signature, in the presence of two witnesses, this 29th day of June, 1899.

GEORGE S. MARSHALL.
